UNITED STATES PATENT OFFICE.

ROBINSON R. STABLER, OF BALTIMORE, MARYLAND.

LOADING-TOOL FOR TIME-TRAIN RINGS.

1,244,387.

Specification of Letters Patent.

Patented Oct. 23, 1917.

Application filed December 23, 1916. Serial No. 138,594.

To all whom it may concern:

Be it known that I, ROBINSON R. STABLER, a citizen of the United States, and a resident of the city of Baltimore, in the State of Maryland, have invented a certain new and useful Improvement in Loading-Tools for Time-Train Rings, of which the following is a specification.

My invention relates generally to loading tools for the time train rings of shrapnel shells, and is more particularly a combination of parts used for the purpose of holding the time train rings when filling their powder grooves, and when pressure is applied to thoroughly pack the powder in the grooves.

The primary object of my invention is to provide a novel construction, arrangement, and combination of parts whereby to materially reduce the considerable number of parts now employed for this purpose, and in this way reduce to a minimum friction between parts and the danger of explosion, and a further object is to provide a simple and novel arrangement whereby the operation upon each ring may be accomplished more quickly, more effectively, and consequently at greatly reduced expense and increased efficiency.

30 In the accompanying drawings illustrating my present tool, and forming a part of this specification:

Figure 1 is a top plan view of the complete tool;

35 Fig. 2 is a vertical sectional view taken therethrough, substantially on line 2—2 of Fig. 1;

Fig. 3 is a view similar to Fig. 2, with the punch in position and showing the tool 40 beneath a power plunger for packing the powder;

Fig. 4 is a view similar to Fig. 3, illustrating the plunger lowered and the powder packed, the section of the holder being taken 45 on line 4—4 of Fig. 1, however;

Fig. 5 is a sectional view through the holder, with the fuse ring therein;

Fig. 6 is a detail perspective view of the fuse ring removed, and

50 Fig. 7 is a detail perspective view illustrating parts of the punch and the core member.

Referring now to these figures, I have shown in Fig. 6, a time train or fuse ring 55 at 10, and which is tapered as usual, the upper broader surface being provided with a groove 11 extending almost fully there-

around, with its ends spaced apart, to receive the powder which, in the process of introduction within the grooves, is packed 60 under high pressure in order to effect a slow burning and prevent its flaring up as loose powder will do.

The tool whereby the loading of the ring may be accomplished, comprises in accordance with my invention, a holder 12, core member 13, powder guide 14, and a punch 15', the holder 12 having an upper inner and annular recess 15, in which the powder guide 14 is disposed, as seen in Figs. 2, 70 3, and 4. The holder 12 also has an intermediate seat 16 of lesser diameter than the seat 15, with the wall 17 thereof tapered in order to receive the fuse or train ring 10, the lower smaller face of which seats upon the seat 16, and the tapered annular face of which seats against the tapered wall 17, the holder 12 having further a lower constricted opening 18 which receives the lower reduced extension 19 of the core member 13. 80 It will be noted that the powder guide 14 has a lower inner annular portion which seats upon the outer upper surface of the time train ring inwardly beyond the outer edge of the latter, in order to follow up and rest upon 85 rings of different thicknesses contained within the intermediate conical seat and also to prevent the powder guide from resting on burs or irregularities at the outer edge of the rings caused by graduations on 90 the outer conical surface thereof.

The core member 13 is provided with an intermediate annular portion 20 which interfits the time train or fuse ring 10, and serves as a support for the inner wall of 95 said ring, as clearly seen in the figures last above mentioned, and its upper body portion extends above the upper broader face of the time ring 10 in spaced relation to the inner peripheral face of the powder guide ring 14, 100 so as to provide an annular channel 21, a part of which is taken up by a plug 22, such as seen in Figs. 1, 4, and 7, attached to the body of the core member 13, and covering that portion of the upper face of the time 105 train or fuse ring 10 between the ends of its groove 11.

The powder guide ring 14 has an upper cup-shaped inner portion 23 into which the loose powder is initially fed, with the parts assembled as shown in Fig. 2, the operator tamping the powder into the channel 21, as seen in Fig. 3, providing for the introduction of the curved punch 15' which, when

disposed as shown in Fig. 3, prepares the tool for introduction beneath the power plunger 24, so that when the latter descends upon the punch 15, under the desired pressure, the latter will be forced in the channel 21, packing the powder in the groove 11 to the point shown in Figs. 4 and 5, the power plunger 24 preferably having a lower facing 25, as seen in Figs. 3 and 4.

10 It is obvious that when the power plunger 24 again rises, the packing operation is completed, and it is merely necessary to invert the tool so that the several parts may be readily released from frictional engagement 5 by forcing the core member 13 out of position.

It is furthermore obvious in the operation of packing the powder, that the core member 13, coöperating as it does with the holder 12, effectively prevents any distortion of the time train or fuse ring 10, due to the terrific pressure applied in the packing of the powder, and that, due to the minimum number of parts required in the construction my invention provides, friction is reduced and danger of sparks materially lessened. In this way explosions rarely occur in the use of the tool proposed by my invention, and even should a spark be thrown into the powder, the fact 30 that the core member 13 and the powder guide 14 are loosely disposed relative to the holder 12, permits of their relative movement with respect to the holder should the powder catch fire, and thus permit of burning 35 of the powder and escape of the gases with the danger from an explosion reduced to a minimum.

My invention as proposed reduces by about one half the number of parts now required 40 in the constructions in use for the same purpose, and my invention is thus capable of much more inexpensive production, and materially reduces the cost of the operation upon each time train or fuse ring, owing to 45 the reduction of the number of parts to be handled as each ring is inserted within and removed from the tool, as well as to the fact that the several portions of the tool proposed by my invention are readily movable 50 relatively to one another, and singularly free from all connections in the form of bolts, machine screws, and the like requiring the use, in the constructions now utilized for loading time train rings, of other tools such 55 as wrenches, turn screws, and the like.

I claim:

1. A loading tool of the character described comprising a holder having an upper inner annular recess, an intermediate 60 ring seat, and a lower constricted opening, a core member extending loosely within said holder having an intermediate annular seat adapted to interfit a fuse ring seated on the

said ring seat, and a lower reduced portion interfitting the constricted opening of the 65 holder, and a powder guide loosely disposed within the upper annular recess of the holder, having an upper powder receiving cup and having its inner periphery spaced from the said core member to form a powder 70 channel above the fuse ring groove.

2. A loading tool of the character described comprising a holder, a core member within the holder, and a powder guide seated within the upper portion of the holder around the said core member and spaced from the latter to form a powder channel around the core member, said holder and said core member having spaced annular 75 portions below the powder guide between which to receive a fuse ring, for the purpose described.

3. A loading tool of the character described comprising a holder, a core member within the holder, and a powder guide seated within the upper portion of the holder around the said core member and spaced therefrom, said holder and said core member having annular portions between which to receive a fuse ring, said core member and said powder guide being loosely disposed in the holder and relatively movable with respect thereto in operation.

4. A loading tool of the character described comprising a holder, a core member 95 for disposition within the holder, and a powder guide for disposition within the upper portion of the holder around and in spaced relation to the upper portion of the core member, said core member and said holder being provided with relatively engaging lower portions sustaining the core member in proper position relative to the holder, and said core member and said holder having intermediate portions spaced apart for the reception of a fuse ring and adapted to engage the inner and outer surfaces of the ring to prevent its distortion during the loading operation.

5. A loading tool of the character described comprising an outer holder and an inner core member provided with spaced portions intermediate their ends to receive a time train ring, and to engage the inner and outer surfaces thereof, a powder guide surrounding the core member and spaced therefrom to form a powder channel, said core member and said powder guide being loosely disposed relatively to the holder, and movable with respect thereto in operation, for the purpose described.
